UNITED STATES PATENT OFFICE.

ANNA FEIGHOR RUSS, OF ROCK ISLAND, ILLINOIS.

DESIGN FOR A DOLL.

52,346.

Specification for Design. Patented Aug. 27, 1918.

Application filed March 15, 1918. Serial No. 222,750. Term of patent 3½ years.

To all whom it may concern:

Be it known that I, ANNA FEIGHOR RUSS, a citizen of the United States, residing at Rock Island, in the county of Rock Island and State of Illinois, have invented a new, original, and ornamental Design for Dolls, of which the following is a specification.

The figure is a front elevation of a doll embodying my design.

What I claim, is:

The new and ornamental design for a doll, as shown.

In testimony whereof I affix my signature.

ANNA FEIGHOR RUSS.
